UNITED STATES PATENT OFFICE.

JOHN BIZON, OF BRETZ, WEST VIRGINIA.

COMBINED STRETCHER AND BODY-CARRIER.

1,131,987.

Specification of Letters Patent.

Patented Mar. 16, 1915.

Application filed June 22, 1914. Serial No. 846,523.

To all whom it may concern:

Be it known that I, JOHN BIZON, a subject of the Emperor of Austria-Hungary, residing at Bretz, in the county of Preston and State of West Virginia, have invented certain new and useful Improvements in Combined Stretchers and Body-Carriers, of which the following is a specification.

This invention relates to certain new and useful improvements in combined stretchers and body carriers.

An object of the invention is to provide a body support in the form of a stretcher that may be used to convey the body of an injured soldier or other person, and employing a body harness that may be easily and quickly attached to the body of the carrier.

A further object of the invention is to provide a stretcher composed of foldable hinged sections that may be caused to assume a chair position so that the body will rest upright while the legs will be directed downwardly.

With the above general objects in view and others that will appear as the nature of the invention is better understood, the same consists of the novel construction, combination and arrangement of parts to be hereinafter more fully described and then claimed.

In the accompanying drawings which show the preferred embodiment of the present invention and to which reference is had wherein by like characters designating corresponding parts throughout the several views:—Figure 1 is a perspective view of the device. Fig. 2 is a rear elevational view of the same. Fig. 3 is a detail side elevational view of a portion of the device showing in detail the clasp for holding the hinged outer end of the device in horizontal position. Fig. 4 is a detail sectional view of a portion of the device illustrating the side guard plate and the position assumed by the same in dotted lines. Fig. 5 is a detail sectional view of the leg and brace connection, and Fig. 6 is a detail sectional view, illustrating the preferred method of attaching the ends of the straps to the frame.

Briefly described, the invention embodies in a single structure, a combined stretcher and body carrier and comprises a frame formed of foldable hinged sections employing a body harness that may be easily and quickly attached to the body of the carrier and be supported on the carrier's back. Suitable leg supports and leg braces are

provided so that the same may be caused to assume a chair-like position as shown in Fig. 1. For purposes of shipping and storing the device, the same may be folded to assume a minimum of space, it being thought unnecessary to show the device in such folded position as the several hinged connections are believed to render the same readily apparent.

Referring more in detail to the accompanying drawings, the reference numeral 10 designates the main side rails having hinged thereto as at 11 the forward extension side rails 12, similar hinge connections 13 carried by the rear ends of the side rails 10 constituting a connection with the rear or back side rails 14. The several sections constituting the side rails are connected by the back supports 15, the bottom support 16 and the front slatted supports 17.

Means are provided to cause the forward hinged sections 12 to assume an alined horizontal position with the main side rails 10 and comprises in detail a sheet metal resilient fastening strip 18 secured as at 19 to the forward ends of the side rails 10 and having the intermediate portion thereof upwardly curved as at 20 and with the forward end overlying the forward side rails 12. The outer ends of the members 18 are slotted as at 21 and receive in said slots the heads 22 of complemental fastening bolts 23, the closed outer end of the slot as shown in Fig. 3 adapted to be seated under the head 22 of the said bolt and hold the said sections in alined horizontal position as shown in Fig. 3. To support the outer ends of the forward extensions 12 when in horizontal position as shown in Fig. 1, I provide a pair of legs 24 with a cross-brace 25 and hinged as at 26 to the said forward rails, the particular shape of the upper ends of the legs 24 adapted to limit the forward movement of the said legs as clearly shown in Fig. 3.

The main side rails 10 are supported at their rear ends by the legs 27 hinged to the said main rails in a manner similar to the forward legs 24. The contacting faces of the main side rails and the back side rails are of such shape as to limit the reclining movement of the rear section, as clearly shown in Fig. 1, the rear section being further supported by the brace rods 28 comprising a cross-brace arm 29 and hinged at their upper ends as at 30 to the rear face of the back support 15. The connection be-

tween the lower ends of the brace rods 28 and the rear supporting legs 27 is clearly shown in Fig. 5 and consists of a collar 31 preferably formed of thin sheet metal to be received on the lower end of the rod 28 and provided with a resilient extension 32 having the hooked end 33 received in the cut-out portion 34 provided in the lower ends of the legs 27 and in such position, engaging 10 the inner face of a sleeve member 35 received on the lower end of the leg 27. In this position the lower end of the rod 28 is also received in the recess 34 and is prevented from being removed by the hook 33, 15 it being necessary to operate the spring arm 32 to release the hook from the sleeve 35 so that the said end of the leg may be released.

When the device is to be used as a carrier or for conveying a body on the back of a 20 person, I preferably provide on one side of the device and hinged to one of the front side extension rails and one of the back side extension rails, body guards 36, such hinged connection comprising angle plates 37 suitably-positioned about the side rails as shown 25 in Fig. 4 and having one end thereof as at 38 secured to the pin 39 formed on the body guard 36. Each of the body guards carries a stop lock 40 on its outer face which limits 30 the same in its unfolded position, the lower end of the guard adapted to engage the side rails as shown in Figs. 1 and 4. In order to hold the device the desired distance from the body of the carrier and to provide a body- 35 engaging support, I provide a block 41 having a suitably curved face for engagement with the body of the carrier. The harness for attachment to the body of the carrier and connected to the frame consists of a pair 40 of straps 42 crossed as at 43 and having one end looped about a ring 44 carried by a U-shaped clamp member 45 secured to the side rails, such construction being clearly shown 45 in Fig. 6. The other end of the crossed strap is secured by an eye connection 46 to the strap 47 carried by similar clamp members 45 on the side rails 10 and 14. The opposite ends of the crossed straps are looped 50 to provide an adjustment and carry at the outer ends thereof, hooks 48 adapted to be received in eyes 49 carried by straps 50 secured by similar clamp members 45 to the opposite side rails of the device. On the 55 rear face of the back supports 15, I have illustrated additional strap supports 51 that may be utilized with an additional strap harness when it is desired to support the back of the stretcher or carrier on the back of a person.

60 In operation, when the device is in the position shown in Fig. 1, the resilient sheet metal fastening members 18 will hold the forward extensions 12 in horizontal position

and prevent the collapse of the same, while the forward end of the device is supported 65 on the front legs 24, the main section 10 being supported on the rear legs 27 while the back 15 is braced by the rods 28 engaging the lower ends of the legs 27, such engagement constituting a lock as clearly 70 shown in Fig. 5. When it is desired to fold the same for purposes of shipment or storage, the spring extension 32 on the collar 31 is engaged by the finger and the hooked end 75 33 is released from the collar 35 which will permit the brace rods 28 to swing on their hinges 30 while the back section 15 swings on the hinges 13 to assume a position juxtaposed to the main section 10. Pressure on the raised intermediate portion 20 of the fastening members 18 will release the forward ends of the said fastening members from the heads 22 of the bolts 23 to thereby permit the forward extensions 12 with the legs 24 swung to a position adjacent the same to 85 lie in contact with the main section 10 by swinging on their hinges 11. In such position, the body guards 36 assume the dotted line position shown in Fig. 4.

When the device is to be used as a carrier, 90 the straps 42 constituting the body harness are secured to the body of the carrier in which position the block 41 engages the back of the person and holds the device in spaced relation so that the body movements are not 95 hindered.

While I have herein shown and described the preferred embodiment of my invention, I do not wish to confine myself to the exact details of construction shown as various 100 forms, modifications and arrangement of the parts as shown may be had without departing from the spirit and scope of the invention as claimed.

What I claim as new is:

In a device of the class described, a frame embodying folding side bars and rear supporting legs and brace rods, each supporting leg having a recess therein adjacent the lower end, a sleeve mounted on the lower end of each leg with an opening therein adapted to register with the leg recess, a collar mounted on each brace rod, and a resilient hooked arm projecting downwardly and outwardly from said collar and rod, 110 said rod end and hooked arm adapted to be received in said leg recess with the hooked arm engaging said sleeve to hold the rod and leg in locked condition and prevent 115 accidental displacement.

In testimony whereof I affix my signature in presence of two witnesses:

JOHN BIZON.
